US0D1105128S

(12) **United States Design Patent** (10) Patent No.: **US D1,105,128 S**
Yu et al. (45) Date of Patent: ** Dec. 9, 2025

(54) **DISPLAY SCREEN WITH GRAPHICAL USER INTERFACE**

(71) Applicant: **Anker Innovations Technology Co., Ltd.**, Changsha (CN)

(72) Inventors: **Wenjun Yu**, Shenzhen (CN); **Hongzhi Yan**, Shenzhen (CN); **Zhichao Xiong**, Shenzhen (CN)

(73) Assignee: **Anker Innovations Technology Co., Ltd.**, Changsha (CN)

(**) Term: **15 Years**

(21) Appl. No.: **29/968,693**

(22) Filed: **Oct. 17, 2024**

(51) LOC (15) Cl. **14-04**

(52) U.S. Cl.

USPC **D14/489**

CLAIM

The ornamental design for a display screen with graphical user interface as shown and described.

DESCRIPTION

FIG. 1 is a front view of a display screen with graphical user interface showing our new design;

FIG. 2 is a front view of a second embodiment thereof; and, FIG. 3 is a front view of a third embodiment thereof.

The peripheral broken line shows a display screen and a boundary of the claimed design. The broken line forms no part of the claimed design.

1 Claim, 3 Drawing Sheets
